UNITED STATES PATENT OFFICE.

FRANKLIN E. ARNDT, OF GALION, OHIO, ASSIGNOR TO SECURITY METALLIC GRAVE VAULT CO., OF ORRVILLE, OHIO, A CORPORATION OF OHIO.

BURIAL-VAULT.

1,219,217.

Specification of Letters Patent. Patented Mar. 13, 1917.

Application filed January 8, 1917. Serial No. 141,250.

To all whom it may concern:

Be it known that I, FRANKLIN E. ARNDT, a citizen of the United States, residing at Galion, in the county of Crawford and State of Ohio, have invented certain new and useful Improvements in Burial-Vaults, of which the following is a specification.

This invention comprehends certain new and useful improvements in burial vaults, and relates particularly to that type of vault in which one end is open and is designed, after the casket has been inserted into the body portion of the vault, to be closed by a door or closure whereby the vault is hermetically sealed.

To those familiar with the art to which this invention appertains, it is well known that some persons prefer a vault in which the door or closure is fastened in closed position by means of nuts and bolts which are screwed up from the outside, the operation of fastening these bolts giving a feeling of security in contradistinction to that type of vault in which the locking devices are not visible from the outside, but are simultaneously operated by a wrench or tool applied to the revolute actuating device at the center of the door; and it is the primary object of the present invention to provide a practical, durable and very efficient construction of burial vault and closure therefor in which, while there are a relatively large number of fastening devices all visible from the exterior or end of the vault, the operation of securely fastening the door or closure at the end of the vault may be very quickly performed, and the vault thus hermetically sealed.

A further object of the invention is a device of this character in which the fastening devices are so formed and their parts so arranged and correlated, that the locking members that are mounted upon the bolts swiveled in the end door or closure, will be easily and securely held in such position that the closure may be quickly applied to the body of the vault and whereby the initial revolute movement of the bolts will serve to effectively swing the locking members to their operative locking positions into engagement with the rear face or flange with which the open end of the body portion of the vault is provided, means being provided whereby this swinging movement of the locking members will be automati-

cally limited and the subsequent turning of the bolts will serve to draw the end door or closure rearwardly against the flange or a packing interposed between the flange and door so as to effect the desired hermetically sealed joint.

And the invention also aims to generally improve devices of this class so as to render them more useful and commercially desirable.

With these and other objects in view, as will more fully appear as the description proceeds, the invention consists in certain constructions, arrangements and combinations of the parts that I shall hereinafter more fully describe.

For a full understanding of the invention, reference is to be had to the following description and accompanying drawing, in which—

Figure 1 is an end view of a burial vault embodying the improvements of my invention.

Fig. 2 is a fragmentary sectional view on an enlarged scale, the section being taken substantially on the line 2—2 of Fig. 3, looking in the direction of the arrow, and

Fig. 3 is a similar view at right angles to Fig. 2.

Corresponding and like parts are referred to in the following description and designated in the views of the accompanying drawing by like reference characters.

Referring to the drawing, the numeral 1 designates the body portion of a grave vault of the open end type, provided at its open end with an internal marginal flange 2 against which the door or closure 3 is adapted to abut, or against an interposed packing or gasket 4.

Revolvally mounted in the door 3 around and near the edge or margin thereof, is any desired number of bolts 5, said bolts being swiveled in openings formed in the door as best illustrated in Fig. 3, and being provided at their outer ends with polygonal heads 6 whereby wrenches or similar tools may be easily applied thereto and the bolts thereby turned. Preferably lead or similar washers 7 are interposed between the rear sides of the heads 6 and the adjacent front face of the door or closure 3.

The shanks of the bolts 5 are threaded, as at 8, and mounted upon the threaded shanks are locking members 9. Each lock-

ing member is preferably formed with an interiorly threaded boss 10, the threads of which engage and work upon the threads 8 of the bolt shanks, and with oppositely directed arms 11 and 12, as clearly illustrated in Figs. 2 and 3. The arm 11 is preferably curved although the invention is not limited in this regard, and is adapted to abut against the rear face of the closure 3, and the opposite arm 12 is preferably formed on one side with a protuberance or bulged portion 13 adapted to bear upon and against the rear side of the flange 2, and with a laterally extended shouldered portion 14 adapted to abut against the side wall of the body portion 1 of the vault to limit the turning movement of the locking member in one direction.

Preferably springs 15 are coiled around the shanks of the bolt 5 and expand against the locking members 9 and the rear face of the closure 3 whereby all rattling of the locking members will be prevented while at the same time the locking members will be held by the expansive action of the springs against any accidental turning movement so that they may be easily adjusted and maintained in such position as to not interfere in anywise with the application of the door or closure to its proper position. Preferably also each bolt 5 is provided at its rear end with a transverse opening extending therethrough for the reception of a cotter pin 16 to prevent the locking members from being backed off of the shanks of the bolts and lost.

From the foregoing description in connection with the accompanying drawing, the operation of my improved burial vault and locking devices therefor will be apparent. In the practical use of the vault equipped with the improvements of my invention, after the casket has been placed in the body of the vault, the closure 3 is moved to its accustomed position, the locking members being so positioned or held that the arms 11 and 12 will pass the inner edge of the flange 2 and not interfere with the application of the closure or door. After the door has been applied the bolts 5 are turned in a direction to swing the arms 12 of the locking members 9 over, that is, behind, the flange 2, with the bulged portions or protuberances 13 in engagement with the rear face of the flange, the abutment of the shoulders 14 or lateral extensions of the arms 9 against the side of the body portion 1 of the vault limiting this turning movement of the locking members as is manifest, whereupon the bolts 5 may be continued to be turned and thus draw or compress the closure 3 rearwardly or inwardly against the flange 2 or the interposed packing or gasket 4 and thus hermetically seal the vault. It will thus be seen that I have provided a very practical, dura-

ble and efficient construction of vault closure and locking devices therefor which will enable the vault to be very quickly, easily and silently sealed, the parts being so constructed that they will not be liable to get out of order or readily become broken.

While the accompanying drawing illustrates what I believe to be the preferred embodiment of my invention, it is to be understood that the invention is not limited thereto, but that various changes may be made in the construction, arrangements and proportions of the parts without departing from the scope of the invention as claimed.

What is claimed, is:

1. The combination with a vault, the body portion of which has an opening and a flange defining said opening, of a door insertible in said opening, and a plurality of locking devices carried by said door, said locking devices comprising bolts revolvably mounted in the door and locking members threaded on said bolts at the rear side of the door, said locking members having arms adapted to bear against the rear side of the flange and formed with shoulders adapted to abut against the body of the vault to limit the turning movement of the locking members in one direction, for the purpose specified.

2. The combination with a burial vault, having a casket receiving opening, and a flange defining said opening, of a door applicable to said opening, and a plurality of fastening devices carried by said door, said fastening devices comprising bolts carried by said door and revolvably mounted therein, and locking members threaded on said bolts at the rear side of the door, said locking members being provided with arms formed with protuberances adapted to engage the rear side of the flange and with laterally extended shoulders for engagement with the body of the vault to limit the turning movement of said locking members in one direction.

3. The combination with a burial vault having a casket receiving opening, and a flange defining said opening, a door applicable to said opening, and fastening devices carried by said door, said fastening devices comprising threaded bolts revolvably mounted in the door, and locking members threaded on said bolts at the rear side of the door, said locking members being provided with oppositely extending arms, one of which is adapted to bear against the rear side of the door and the other to engage the rear side of the flange.

4. The combination with a burial vault having a casket receiving opening, a flange defining said opening, of a door applicable to said opening, and fastening devices carried by said door, said fastening devices comprising threaded bolts revolvably mounted in the door, and locking members threaded on

said bolts at the rear side of the door, said locking members being provided with oppositely extending arms, one of which is adapted to bear against the rear side of the door and the other to engage the rear side of the flange, said last named arm being provided with a lateral extension adapted to abut against the body of the vault to limit the turning movement of the locking members in one direction.

5. The combination with a burial vault having a casket receiving opening, and a flange defining said opening, of a door applicable to said opening, and a plurality of 15 fastening devices carried by said door, said fastening devices comprising threaded bolts revolvably mounted in said door, locking

members threaded on said bolts at the rear side of the door and each provided with oppositely extending arms, one of which is 20 adapted to bear against the rear side of the door and the other against the rear side of the flange, said last named arm being formed with laterally extending shoulders, for the purpose specified, and expansion springs 25 coiled around said bolts and bearing against the locking members and said door.

In testimony whereof I affix my signature in the presence of two witnesses.

FRANKLIN E. ARNDT.
